CLAIM

The ornamental design for an air conditioner, as shown and described.

DESCRIPTION

1. Air conditioner

- 1.1 : Perspective
1.2 : Front
1.3 : Back
1.4 : Left
1.5 : Right
1.6 : Top
1.7 : Bottom

The broken lines depict portions of the air conditioner that form no part of the claimed design; reproduction 1.1 is a bottom perspective view of the air conditioner; reproduction 1.2 is a front view thereof; reproduction 1.3 is a back view thereof; reproduction 1.4 is a left view thereof; reproduction 1.5 is a right view thereof; reproduction 1.6 is a top view thereof; reproduction 1.7 is a bottom view thereof; this is a design for an air conditioner which can be installed on the ceiling.

1 Claim, 7 Drawing Sheets
